UNITED STATES PATENT OFFICE.

JAMES H. TAYLOR, OF NEW YORK, N. Y., ASSIGNOR TO THE AMERICAN LAUNDRY MACHINERY COMPANY, OF CINCINNATI, OHIO, A CORPORATION OF OHIO.

PADDING.

Application filed April 18, 1924. Serial No. 707,459.

This invention relates to yielding or resilient padding such as is used on pressing or ironing machines, either of the relatively movable upper and lower platen type, or 5 flat work ironers including padded rolls operating with heated concave platens or the like.

The object of the invention is to provide improved resilient padding adapted to be 10 carried by or mounted upon a suitable support, either curved or flat, and including a plurality of individual yieldable and preferably composite members which may be individually placed, replaced or repaired, and 15 which together provide the necessary uniformly yielding surface to receive the material or fabric to be pressed, and which need only be covered by relatively light cover material, thereby doing away with material or 20 appreciable thickness of cellulose padding of the usual form. The invention is an improvement upon the form of padding shown, described and claimed in my copending application for padding, filed of even date 25 herewith, Serial No. 707,458. The particular feature of the present improvement is a special mounting of the yieldable pad members and the employment not only of yielding lower springs therewith but of hinged 30 or movable connections of the upper spring members to the supporting member.

Further objects of the invention will be more apparent from the description to follow.

35 In the drawings, Fig. 1 is a detail section on the line 1—1, Fig. 3 of a portion of the roll of a flat work ironer embodying the invention; Fig. 2 is a detail section on the line 2—2, Fig. 1; Fig. 3 is a plan view, part of 40 the buttons or upper pad members being shown in skeleton form by dot and dash lines for better illustration of the parts therebeneath; Fig. 4 is a detail view, corresponding to Fig. 2, and illustrating a 45 modification; and Fig. 5 is a plan view thereof.

In the drawings, 1 represents a portion of 50 a hollow cylindrical wall of the roll of a flat work ironer, or in other words, the member upon which the yieldable pad is mounted and which may obviously be a flat or plain surface member in the case of a platen type press. The spring pad to be described may be carried by a separate member 55 mounted upon the roll or platen bed, but

as shown said pad comprises a plurality of individual resilient members attached directly to the roll body 1. As said pad members are alike description of one will suffice for all.

Each resilient pad member includes an upper member 2 of button form and one or more independently resilient lower members 3, member 2 being superimposed upon member 3. Members 2 are inherently resilient to 60 any desired degree. They may be of any suitable material for the purpose, preferably some material which is heat resistant or heat insulating to the extent that they oppose or retard transmission of heat to the parts 70 which support them and withstand the effects of the heated platen or member with which the pad contacts without destruction or breaking down within a reasonably durable life. Several materials are suitable for 75 the purpose, such as cork, compositions containing cork or other like materials and a binder, rubber or rubber compositions or asbestos with or without the necessary binder 80 to hold it together and give it the required 85 resiliency. Usually the buttons are made of a material which may be molded. The lower pad members, in the form shown, are spiral springs, which at their lower ends rest loosely upon the roll body and at their upper ends have one or more coils held and secured to the button in any suitable manner. In Fig. 1 the springs are secured at their 90 upper ends by screws 4, while in Fig. 4, where two springs support each button the upper ends of the springs are molded into the buttons, as indicated at 5.

Each button has connected thereto an arm or strap 6 which forms the connection tying it to the roll body, for which purpose the 95 straps at their lower ends are bent to form eyes 7 to receive a portion of a wire loop 8 fastened to the roll body by the screw 9.

In Fig. 4, where the buttons are oblong rather than square and are supported by 100 two springs, the attaching strap 6 is connected by a screw to the button between the two springs.

With this arrangement the several buttons, closely spaced as shown in Fig. 3, have 105 independent movement, each one swinging toward the roll body about the hinge axis, but, of course, are confined by said hinges and cannot escape. Each yielding pad member, including its upper button 2 and a 110

spring or springs 3 can be repaired or renewed independently of all others, by merely removing the screw 9 which fastens the hinge loop to the roll body, or where the screws 4 are used for attaching the springs and buttons to each other, a button may be replaced by removing said screw.

8 The several pad buttons supply a uniformly resilient and practically continuous 10 surface which may be covered by a suitable cover cloth 10 if desired.

What I claim is:

1. An ironing device, comprising a body, a plurality of adjacent heat-insulating members, movable connections between the same and said body so that said members are capable of movement towards and from the body, and resilient bearing means therefor between said body and members.

20 2. An ironing device, comprising a body, a plurality of adjacent heat insulating members, movable connections between said members and said body so that said members are capable of movement toward and from the 25 body, and resilient bearing means therefor between said body and said members and free of connection to one thereof.

3. An ironing device, comprising a body, a 30 plurality of adjacent heat insulating members, movable connections between said members and said body so that said members are capable of movement toward and from the body, and resilient bearing means therefor between said body and said members and 35 free of connection to said body.

4. An ironing device, comprising a body, a 40 plurality of adjacent heat insulating members, movable connections between said members and said body so that said members are capable of movement towards and from the

body, and resilient means therefor secured to said members and having bearing engagement with said body.

5. An ironing device, comprising a body, a plurality of adjacent heat-insulating members hinged to said body so as to be capable of movement towards and from the same, and resilient bearing means between said body and members.

6. An ironing device, comprising a body, a plurality of adjacent and heat-insulating members, hinge connecting means between said members and body so as to permit movement of said members towards and from said body, and resilient bearing means between said body and members, said bearing means being connected to said members at the points of connection of said hinge means.

7. An ironing device, comprising a body, a plurality of adjacent heat-insulating members, said members being provided with movable connections to said body so as to permit movement of the same towards and from said body, and resilient bearing means between said body and members, said bearing means being connected to said members at the points of connection of said movable connections thereto.

8. An ironing device, comprising a body, a plurality of heat-insulating members having individually disconnectible hinge connections to said body so as to permit movement of the same towards and from said body and ready removal of said members, and resilient bearing means between said body and members.

In testimony whereof I hereby affix my signature.

JAMES H. TAYLOR.
